UNITED STATES PATENT OFFICE.

ALFRED E. LEMON, OF DOUGLAS, ARIZONA.

DEEP-SEA SALVAGE APPARATUS.

1,415,661.

Specification of Letters Patent.

Patented May 9, 1922.

Application filed December 30, 1919. Serial No. 348,817.

To all whom it may concern:

Be it known that I, ALFRED E. LEMON, a citizen of the United States, and a resident of Douglas, in the county of Cochise and State of Arizona, have invented a new and Improved Deep-Sea Salvage Apparatus, of which the following is a full, clear, and exact description.

The object of the invention is to provide a new and improved deep sea salvage apparatus, more especially designed for doing salvage and similar work on sunken vessels or other parts located at great depth.

Another object is to permit of maintaining a practically normal air pressure within the apparatus irrespective of the depth it is in at the time, thus enabling the occupant or occupants to work without danger of being subjected to high air pressures so detrimental to health.

Another object is to permit of lowering the apparatus to the desired depth from a mother ship or raising it to the surface without loss of valuable time.

Another object is to enable the occupant to fasten grappling or similar devices to a sunken vessel or other object with a view to raise the same or perform other desired work.

Another object is to permit of running the apparatus along the sea bottom for locating a sunken vessel or for exploration or other purposes.

With these and other objects in view, the invention consists of certain novel features of construction as hereinafter shown and described and then specifically pointed out in the claim.

A practical embodiment of the invention is represented in the accompanying drawings forming a part of this specification in which the figure is a sectional side elevation of the improved deep sea salvage apparatus.

The deep sea salvage apparatus comprises a vessel 10 having a hull 11, preferably of spherical shape, and constructed to readily withstand deep water pressure when lowered to the bottom of the sea. The hull 11 is provided exteriorly at the bottom with a ballast receptacle 12 filled with suitable ballast 13 to cause the vessel 10 to sink to the desired depth. The top of the hull 11 is provided with an eye 14 engaged by a cable 15 connected with a windlass or other suit-

able apparatus on board of a "mother" ship 55 to permit of lowering or raising the vessel 10.

Two air pipes 20 and 21 of a non-collapsible nature are attached to the hull 11 and open into the vessel to circulate air within 60 the hull approximately under normal or atmospheric pressure. The pipes 20 and 21 are connected with the mother ship and one of the pipes is connected with a pump or other suitable apparatus for forcing air 65 through the pipe into the vessel under an approximately atmospheric pressure. The other pipe serves for the escape of the vitiated air incident to the exhaling of the air by the occupant or occupants of the vessel 10. The pipes 20 and 21 are provided with suitable valves 22 and 23, which are normally open but can be closed in case of an emergency. The hull 11 is provided near the top with a suitable manhole 25 for the 70 ingress or egress of the person or persons confined in the vessel 10. The manhole 25 is provided with a suitable cover 26 which is held locked in closed position after the person or persons have passed into the vessel at 75 the time the latter is at the surface of the water.

Within the hull 11 and preferably at the floor 30 thereof is arranged a bilge pump 31 having its suction pipe 32 extending to the 85 bottom of the hull and having its discharge pipe 33 extending through the hull and the ballast casing 12 to allow of pumping the bilge water out of the vessel into the surrounding water.

Within the hull 10 is arranged a motor 40, preferably of the electric type, and mounted on a bracket 41 attached to the hull 11 at the inside thereof, and the shaft 42 of this motor is connected by a reversible clutch 43 95 with a propeller shaft 44 journaled in a suitable bearing 45 arranged in the hull 11, preferably at the middle of the height of the hull, as plainly shown in the drawing. The outer end of the propeller shaft 44 carries a 100 propeller 46 to permit of moving the vessel along when submerged either for locating the sunken vessel or for exploring the sea bottom or for other purposes. The clutch 43 is provided with a suitable clutch lever 105 47 to permit of connecting or disconnecting the shafts 42, 44 whenever it is desired to do so.

A rudder 50 is mounted to swing on brackets 51 and 52 attached to the outside of the hull 11 above and below the propeller 46, and the lower pivot 53 of the rudder 50 is connected by bevel gearing 54 with a shaft 55 journaled in a bearing 56 arranged in the hull 11. On the inner end of the shaft 55 is secured a steering wheel 57 under the control of an occupant of the vessel 10 to turn the rudder 50 with a view to steer the vessel in a desired direction.

A manually controlled gripping device 60 is mounted in the wall of the hull 11 and is constructed as follows: A joint formed of a ball 61 and a socket 62 is secured in the hull 11, and in the ball 61 is mounted to slide a tube 63 connected at its outer end by links 64 with two gripping jaws 65 mounted to swing on the pivot 66 held on the outer end of a rod 67 mounted to slide in the tube 63. The inner end of the rod 67 extends within the hull 11 and on the inner end is secured a nut 68 in which screws a screw rod 69 mounted to turn at one end in a bearing 70 attached to the inner end of the tube 63. The screw rod 69 is provided with a crank arm 71 under the control of an occupant of the vessel to permit the occupant to turn the screw rod 69 with a view to move the rod 67 outward according to the direction in which the screw rod 69 is turned at the time. On moving the rod 67 outward the jaws 65 are closed to grip a part exteriorly of the vessel 10. On moving the rod 67 inward the jaws 65 are opened to release the part previously gripped. It will be noticed that by mounting the gripping device in the ball 61 it can be readily swung into a desired position for the jaws 65 to grip a part located exteriorly of the vessel 10. It will also be noticed that the tube 63 can be readily moved inward or outward on the ball 61 to properly locate the jaws 65 relative to the object to be gripped.

A ball and socket joint is formed by a ball 80 and a socket 81 in the hull 11 above the gripping device 60, and in the ball 80 is mounted a telescope 82 to permit the occupant to obtain a clear view of the parts to be gripped or explored. Below the gripping device 60 is arranged a searchlight 90 to illuminate the object to be gripped by the gripping device 60. Below the searchlight 90 is arranged a bearing 95 in which is mounted to turn and to slide the shaft 96 carrying at its outer end a drill 97 and connected at its inner end with a motor 98 mounted to slide on a guideway 99 attached to the hull 11 at the inside of the vessel. A feed screw 100 is mounted to turn in a bearing 101 attached to the hull 11, and the said feed screw 100 screws in a nut 102 forming part of the motor 98. A feed wheel 103 is attached to the feed screw 100 to permit 65 of moving the motor 98 forward or back-

ward and thus feed the drill 97 into the work to be drilled, or out of the drilled hole, according to the direction in which the feed wheel 103 is turned at the time. A powerful magnet 110 is attached to the ballast casting 12 to permit of fastening the vessel 10 by magnetic power to an iron vessel or other metallic object to be explored at the time. It will be noticed that this magnet 110 is especially necessary when using the drill 97 so as to provide the desired hold of the vessel 10 on the object to be drilled. Within the vessel 10 is also arranged a telephone 120 and a switchboard 121 having its circuit wires 122 extending through a non-collapsible tube 123 attached to the top of the hull 11 and leading to the mother ship.

It is understood that only one gripping device 60 is shown, but it is evident that more such devices may be mounted on the hull 11. The gripping device may be used for placing hooks or other devices lowered from the mother ship into holes drilled by the drill 97 in the object to be raised by the apparatus on the mother ship. The gripping device can also be used for picking up objects or placing grappling hooks or buckets in position during salvage work.

The apparatus after having been tested and connected up with the mother ship, and with a trained crew placed inside the vessel, is let down in the vicinity of say a sunken ship which is to be salvaged. Arriving near the ocean floor, the crew, directing the depth at which the apparatus is maintained by means of the telephone to the mother ship, can move in a horizontal direction as desired on using the propeller 36 and the rudder 50. The sea floor can thus be explored until the sunken ship is located. The vessel is then moved to a selected point on the side of the ship and held in position thereon by means of the electromagnet 110. The drill 97 is next used to drill a hole in the side of the sunken vessel and then a hook suspended by a steel cable from a pontoon or from the mother ship is let down and by means of the gripping device 60 is engaged with the drilled hole. The apparatus is then moved to another point on the sunken ship, and the above described operation is repeated as often as necessary to attach a desired number of lifting cables to the sunken vessel to permit the sunken vessel to be raised, preferably, by tightening the attached cables to the pontoon at low tide to cause the vessel to be raised on the rising of the pontoon during the rising of the tide. This operation is repeated as often as is necessary until the sunken vessel is raised to the surface of the water.

It is understood that as the tide raises the pontoons and with them the ship below through the attached cables, the pontoons are towed toward the shore at each rise of

the tide until the ship is out of water at low tide. Salvage can then be completed by simple ordinary methods.

It will be noticed that by the use of this 5 cheap easy salvage apparatus it is feasible to save ships and cargoes from depth far beyond reach with an ordinary apparatus.

Having thus described my invention, I 10 claim as new and desire to secure by Letters Patent:—

A gripping device for a deep sea salvage

apparatus, comprising a tube adapted to be mounted in the wall of the body of the apparatus, a rod slideable in the tube, a pair of jaws fulcrumed on the outer end of the said 15 rod, links connecting the said jaws with the outer end of the said tube, a nut on the inner end of the said rod, a screw rod screwing in the said nut and having one end mounted to turn on the said tube, and a handle on the 20 other end of the said screw rod.

ALFRED E. LEMON.
